UNITED STATES PATENT OFFICE.

JOHN H. LANCE, OF WILKES-BARRE, PENNSYLVANIA.

PITCHER.

1,165,787.

Specification of Letters Patent.

Patented Dec. 28, 1915.

Application filed September 30, 1914. Serial No. 864,234.

To all whom it may concern:

Be it known that I, JOHN H. LANCE, a citizen of the United States, residing at Wilkes-Barre, in the county of Luzerne and 5 State of Pennsylvania, have invented certain new and useful Improvements in Pitchers, of which the following is a specification.

My invention relates to new and useful 10 improvements in pitchers and the object thereof is to provide a pitcher with means to return into the pitcher any drippings which would otherwise fall from the pouring lip thereof.

15 A further object of my invention is to provide a device of this character which can be readily and easily cleaned and which can consequently be kept sanitary without difficulty.

20 With the foregoing and other objects in view my invention consists in certain constructions, combinations and arrangements of parts, the preferred form of which will be first specifically described in connection 25 with the accompanying drawings and then the invention particularly pointed out in the appended claim.

Referring to the drawings wherein the same part is designated by the same reference numeral wherever it occurs, Figure 1 is a front elevation of a pitcher provided 30 with the preferred embodiment of my invention; Fig. 2 is a side view of Fig. 1; Fig. 3 is a top plan view; Figs. 4 and 5 are sections on lines 4-4 and 5-5 of Fig. 2; and Fig. 6 is a section on line 6-6 of Fig. 1.

10 designates a pitcher of any ordinary or desired type having the usual pouring lip 40 11 and the sides 12 downwardly inclining from the pouring lip, said lip being shown as concaved on its upper edge, and the sides 12 as being convexly curved, as usual.

13 designates an outwardly extending 45 flange, which as shown, starts from one side of the pouring lip 11 in a downwardly inclined direction around the outside of the pitcher beyond a point 14 on the side of the pitcher beyond where the inclined portion 50 12 terminates, the inclination of the flange 13 being less than the inclination of the side

12 so that the upper edge of the flange crosses the upper edge of the side and at its termination extends into the pitcher. This flange forms an open channel 15, the 55 various cross sections of which are best shown in Figs. 4, 5 and 6 and by having the flange terminate beyond the inclined portion 12, the edge of the flange will rise above the edge of the pitcher proper and cause 60 liquid caught in the portion of the channel immediately beneath the lip to be returned into the pitcher without permitting the liquid to flow down the outer surface thereof. It should be particularly noted 65 that because of the open character of the channel, there is no difficulty in easily washing and cleansing the same and the pitcher is in fact no more difficult to clean than one of ordinary construction. 70

I am aware that considerable variation is possible in the details of construction herein shown and described, without departing from the spirit of my invention, and I do not intend to limit myself thereto, except as pointed out in the following claim, 75 in which it is my intention to claim all the novelty inherent in the structure shown and described as broadly as the state of the art will permit. 80

What I claim as new and desire to secure by Letters Patent is:

The combination with a pitcher having a pouring lip with elevated sides and depressed front edge and said sides extending downwardly and rearwardly to the top edge of the pitcher, of a drip flange integrally formed on said pitcher extending from a point near the upper edge of one side of the lip above the pouring edge diagonally downward and around beneath the pouring edge to a point on the opposite side of the pitcher opening into the pitcher at its top edge whereby a channel is formed to catch the drippings from the lip and conduct the same back into the pitcher. 85 90 95

In testimony whereof I affix my signature in presence of two witnesses.

JOHN H. LANCE.

Witnesses:
